[57] CLAIM

The ornamental design for a baby bunting, as shown and described.

DESCRIPTION

FIG. 1 is a plan view of the inside of a baby bunting showing my new design in open condition;

FIG. 2 is a perspective view of the baby bunting in closed condition;

FIG. 3 is a front elevational view thereof;

FIG. 4 is a left side elevational view, the right side being a mirror image thereof;

FIG. 5 is a rear elevational view thereof;

FIG. 6 is a top plan view thereof; and

FIG. 7 is a bottom plan view thereof.
